The ornamental design for an illuminatable control panel for a range, as shown and described.

DESCRIPTION

FIG. 1 is a front perspective view of an illuminatable control panel for a range according to our new ornamental design; FIG. 2 is a front view thereof;

FIG. 3 is a bottom view thereof showing a plurality of LED lights in broken lines;

FIG. 4 is a top view thereof;

FIG. 5 is a bottom perspective view thereof showing a plurality of LED lights in broken lines; and,

FIG. 6 is a cross section taken along lines 25-25 of FIG. 4. The broken lines are included for the purpose of illustrating portions of the illuminatable control panel for a range that forms no part of the claimed design.

Throughout the drawings, various views may not be provided, as the components in these views are unornamented or the ornamentation in these views is simply unclaimed.
